UNITED STATES PATENT OFFICE.

BARDWELL A. GOODELL, OF WALTHAM, MASSACHUSETTS, ASSIGNOR TO E. HOWARD & CO.

DESIGN FOR WATCH-HANDS.

Specification forming part of Design No. 5,316, dated October 17, 1871.

To all whom it may concern:

Be it known that I, BARDWELL A. GOODELL, of Waltham, in the county of Middlesex and State of Massachusetts, have invented a new and original Design for Watch-Hands; and I do hereby declare that the following is a full, clear, and exact description thereof, which will enable others skilled in the art to make and use the same, reference being had to the accompanying drawing forming part of this specification.

The nature of my design is fully represented in the accompanying drawing, to which reference is made.

A is a crescent-shaped flat piece formed on the bar of the hand a short distance from the point; and B, a diamond-shaped piece on each side of said piece A. The one nearest the point is a little smaller than the other.

I claim as my design for watch-hands—

The crescent-shaped piece A and a diamond-shaped piece, B, arranged on the bar each side of said piece A, substantially as specified.

BARDWELL A. GOODELL.
